COMBINATION LOCK

Louis Paul Georg Ketner, Copenhagen, Denmark

Application November 15, 1935, Serial No. 49,890
In Denmark July 13, 1935

6 Claims. (Cl. 70—298)

The present invention relates to improvements in combination locks of the kind in which a number of locking members, shaped as cylinders, balls or other suitable shape, and, prior to the lock being opened, have been moved by adjustable units, the adjustment of which must be previously known by the person opening the lock.

The distinguishing feature of the present invention consists mainly in that the units, which serve to move the locking members in their bearings, when it is attempted after such adjustment to approach the said units to the locking members or, vice versa, for the purpose of moving the locking members in their bearings and to open the lock, are blocked and held in their position during the further motion of the lock parts, no matter whether the adjustment of the units serving to move the locking members in their bearings be correct or not. By this blocking of the adjustable units the advantage is attained in that the lock is rendered "insensitive", i. e. that it will be impossible, during the motion of the parts, when it is attempted to open the lock, to feel what adjustable units are actuating the corresponding locking members and what units are not doing so.

The invention relates further to various details of the lock, such as the connection between the locking members and the latch bolt proper of the lock, and arrangements causing the blocking of the adjustable units, the displacement of the locking members and the opening of the lock to be effected by the manipulation of one and the same handle or key.

The lock may be used as a bicycle lock as well as for locking of doors, closets, drawers and the like.

The invention is illustrated in the accompanying drawings which embody two constructions of a lock used as a bicycle lock.

Figure 1 showing a lock viewed from the rear with the rearmost cover plate of the lock casing removed,

Figure 2 a section along the line II—II in Figure 1,

Figure 3 a section along the line III—III in Figure 1,

Figure 4 a detail of the lock, in top view,

Figure 5 the same in rear elevation,

Figure 6 another construction of the lock, viewed from behind, in the locked position,

Figure 7 the same in open position with a cover plate removed containing a spring case, and

Figure 8 a section along the line VIII—VIII in Figure 7.

Figure 9 is a detached perspective of two assembled rails and related parts.

Figure 10 is a perspective view of a detached blocking member.

Figure 11 is an elevation of a blocking member shown in assembled relation with reference to the rails illustrated in Figure 9, and shown also in Figures 1 and 3.

Figure 12 is a broken perspective view illustrating the cooperating ends of a latch bolt and locking bolt.

Figure 13 is a perspective view of certain of the operating parts of the mechanism shown in Figures 6 to 8.

Figure 14 is a perspective view of part of the lock operating mechanism illustrated in Figures 6 to 8, and viewed from the right hand side of Figure 8.

Figure 15 is a perspective view of a detached plate forming part of the mechanism of the second modification of the invention, and

Figure 16 is a sectional view of a bicycle lock, partly in section, the latch of which may be controlled by the mechanism of either form of the combination lock illustrated in the preceding figures.

Referring to Figures 1 to 3, 1 is a U-shaped rail, supporting spring-loaded locking members 3 in holes 2, which rail, when the locking members are raised somewhat against the spring pressure, slides in its longitudinal direction in another U-shaped rail 4, the lower flange of which is fitted with holes corresponding to the holes 2 for the locking members 3, which project into these holes when the lock is in its locking position, as shown in the drawings. The rail 4 can slide in the vertical direction of the lock in a couple of incisions 5 on two side members 7 fixed in the lock casing, and during such motion the rail 4 will take along the rail 1 which, as mentioned above, is so guided in the rail 4 that it can slide sideways therein, but on the contrary will be prevented from sliding in the vertical direction of the lock. In Figs. 9 and 11, the rail 1 is shown as provided with lugs 1a which project into elongated slots 4a of the rail 4, which enable the rail 1 to move longitudinally but not vertically with respect to rail 4. One of the lugs 1a may be connected to a spring x which tends to move the rail 1 to the right as viewed in Fig. 11.

The rail 4 also supports, besides the rail 1, a blocking device 8 for a number of sliding units or keys 9 hereafter referred to. The blocking device is shown in detached relation in Fig. 10. In the construction described, the blocking device 55

is formed as a plate extending throughout the entire width of the lock and guided on the rail 4 by a lug 8a or the like which projects into a recess 4b in the rail (see Figs. 9 and 11) so that it can be 5 raised slightly against the pressure from a V-shaped spring 10, in such a manner that the rail 4, when lowered, will carry the plate 8 along, but only until this plate meets a resistance, after which the rail 4 is lowered against the pressure 10 from the spring 10, while the plate 8 is maintained in position. If desired, the blocking plate 8 may have end projections or ears 8c as shown in Figs. 2 and 11, which are guided in slots 8b in side pieces 7. In the lock casing 6, a plurality 15 of sliding units or keys 9 are provided, one below each locking member, each unit 9 being fitted with a tooth 11 and a finger grip 12. When the units 9, by means of the finger grips 12, are moved into position all the teeth 11 come opposite the 20 corresponding locking members, and the teeth 11 will move the said members in their bearings, when the keys 9 and the rail 4 supporting the rail 1 with the locking members 3 are moved towards one another. In the drawings six keys are 25 shown, but may of course be varied as desired, and the teeth 11 are displaced relatively to one another on their keys so that a predetermined number of the teeth 11, when these keys are moved to their "normal position", i. e. the position 30 in which all the finger grips 12 are on a straight line, must be moved in order that all the teeth 11 provided on the keys 9 come opposite their corresponding locking members 3.

The keys 9 are fitted, at the bottom, with notches 35 or incisions 13, the sides of which co-operate with inclined edges 14 on a rail 15 adapted to slide in the lateral direction of the lock.

The sliding keys 9 are further fitted with notches or incisions 16, the number of which is the same 40 for all the keys, and corresponds to the number of positions the keys occupy when all the teeth 11 are opposite the locking members. Three positions are provided for the keys, as shown by Figure 3, and consequently each key is fitted 45 with three incisions 16. These incisions co-operate with the plate-shaped blocking device 8, and serve thereby to maintain the sliding keys in the position given them when an attempt is made to open the lock.

Between the side pieces 7 a rail 17 is provided 50 in which a cam disc 18 is journaled, which can be rotated by means of a handle or a key 19. The disc 18 co-operates with the top surface of the rail 4 in such a manner that by a rotation of 55 the handle or key 19 in the direction indicated by the arrow 20 in Figure 1, the said disc will depress this rail against the pressure of the springs Z, (see Fig. 1), which are adapted to constantly maintain the rail 4 pressed against the lower edge 60 of the disc 18, and also with a lug 21 on a locking bolt 22, which is adapted to slide in the vertical direction of the lock, and is depressed by a spring, such as a spring 21' shown in Figs. 1 and 2 disposed between the hook 21 of the latch bolt 22 65 and the adjacent upper flange of the casing cover 6a whereby the hook 21 is constantly pressed against the top edge of the disc 18. If desired, the spring Y shown in Figure 9 may be substituted for springs Z, illustrated in Fig. 1. The locking bolt 22 is fitted, at the bottom, with a lug 23 co-operating with a lug or the like on a latch bolt 24 of the lock (See Fig. 12). In the construction of the lock shown in the drawings, this lug is formed by one side of a flange or bend on the latch bolt, 70 and the other side of this bend co-operates with 75

a lug 25 on a rail 26 adapted to slide in the lateral direction of the lock and pulled towards the left side of the lock by means of a spring 27 (see Fig. 5).

The rail 26 is connected, by means of a spring 5 28, to the notched rail 15, in such a manner that the rail 26, when moved to the right against the resistance from the spring 27 will take the notched rail 15 along, although this rail can constantly be pushed to the left against the resistance from the 10 spring 28.

The lock operates in the following manner:

When the lock is closed, the parts are occupying the positions shown in Figures 1 to 5, and the keys standing opposite the notches in the rail 15 15 15, the said rail being moved out to its extreme position, to the right on the drawings, by the latch bolt 24, the lug 25, the rail 26 and the spring 28. The keys are now moved into the positions desired. Subsequently, the handle or the key 19 20 is turned in the direction indicated by the arrow 20, whereby the rail 4 with the rail 1 and the blocking device 8 are moved downward, and the blocking plate 8 will then move down into one set of the notches 16 in the keys 12 and block these 25 keys. If the key 19 is turned further, the rail 4 will be moved towards the teeth 11, and if the keys have been adjusted properly so that all the teeth are opposite the locking members, then the teeth 11 will lift the said members up from their 30 holes in the rail 4, and consequently the rail 1 will then be moved in this position. The disc is circular on part of its upper edge corresponding to this rotation, in such a manner that the lug 21 35 will not yet be actuated. But owing to the further shape of the disc, the further rotation of the disc against the pressure from the spring 21' causes the lug 21 and, consequently, the locking bolt 22 to be lifted, and an oblique edge 30 of an incision 28 provided in the locking bolt 22 40 40 will actuate a lug 31 provided on the rail 1 and move the latter, in such a manner that the locking bolt can be raised to an extent that the lug 23 at the bottom of the bolt will become free of the latch bolt 24 of the lock, and by the action 45 of a spring (not shown) the latch will be withdrawn in known manner, and thereby the lock will be opened. At the same time, the lug 25 on the rail 26 will be released from the latch bolt, and by means of the spring 27 the rail 26 will be 50 withdrawn, i. e. towards the left on the drawings, and will take the notched rail 15 along, the oblique edges 14 of the latter co-operating with the edges 13 on the keys 9 and returning the said 55 keys to their normal position, and maintaining them in this position, until the lock is closed again. As long as the lock is open, the bolt 22 will be resting on the latch bolt under pressure exerted by the spring 21' mentioned above. The lock is closed in known manner by moving the 60 latch bolt forward by means of a handle 24a (see Fig. 16) or the like provided on the latch bolt. The latch bolt is moved forward to an extent that the above mentioned bend or flange on the latch has reached beyond the bolt 22, the lug 65 23 of which will then engage the rear side of the bend and maintain the latch in position until the lock is opened again.

If the keys are not adjusted correctly, and when it is attempted to open the lock, the blocking device 8 will engage the notches, but a further rotation of the handle or key will merely have the effect that the teeth on the incorrectly adjusted keys will press against the bottom side of the rail 4, and the blocking of the keys will 75

render it impossible to feel what keys have their teeth 11 standing opposite the corresponding locking members, and what keys have their teeth 11 resting on the rail 4 .

The lock may be assembled in various manners. In the above described construction shown in Figures 1 to 5, the above mentioned parts, except the lock casing 6 , are assembled and then held together by means of two pairs of pins or split pins 32 and 33 , the rail 17 being fitted at the ends with lugs 34 adapted to be inserted through corresponding holes at the top of the side pieces 7 , and with holes corresponding to the parts 32 , in which holes the said parts can be fastened. At the bottom the lock may be assembled in similar manner, an assembling rail 36 being provided between the lower parts of the side pieces 7 and fitted with lugs 35 corresponding to the lugs 34 and passing through corresponding holes in the bottom part of the side pieces and being fitted with holes for the pins or split pins 33 . After the parts have been brought into their proper mutual positions, the pins or split pins 32 and 33 are placed in their holes in the lugs 34 and 35 , respectively, and the parts thus assembled are then pressed down into a hollow portion $6a$ of the lock casing 6 , which for this reason is divided into a hollow portion $6a$ and a cover $6b$, which latter after the lock parts have been inserted into the hollow portion is attached thereto by means of screws or the like provided at suitable points, and serves to fix the parts in the lock casing by fitting tightly about the same by means of guide strips or guide lugs.

As shown in Figure 3, the rail 36 may be made U-shaped, and may serve to guide the sliding rail 26 . The flange of the latter in this case is fitted with an incision 37 for the lug 25 provided on the rail 26 and projecting out through the said incision. The sliding notched rail 15 may similarly be guided in a U-shaped rail 38 , the upper flange of which has incisions for the lugs 13 .

The lock may be built in the so-called "Mecano" style, in such a manner that a set of coordinate parts can be bought and assembled by the buyer so as to form different locks, the latter being varied by an interchange of the parts 9 , as any combination of these parts will correspond to a new lock.

Figures 6 to 8 show a modified construction of the lock described above. In this construction, a rail 56 does not support the locking members but, on the contrary a rail 59 corresponding to rail 4 encloses the rail 56 and is adapted to slide in the lateral direction of the lock. The rail 56 has not a U-shaped but a quadratic or rectangular cross-section. The rail 59 is fitted with holes 57 for the locking members 58 , shaped as balls, which by springs 60 are pressed up against the central bars of a grid, forming in this construction of the lock, the blocking device $8'$ for the sliding keys $9a$, the locking members 58 projecting through holes, corresponding to the holes 2 , in the rail 59 which in this construction of the lock is adapted to slide in the lateral direction of the lock. Likewise as in the construction described in connection with Figures 1 to 5, the keys $9a$ are fitted with teeth $11a$ co-operating with the locking members 58 . The rail 56 as well as the bars forming the grid constituting the blocking device $8'$ are disposed as fixed connecting links between two rails 39 adapted to slide in the vertical direction of the lock, so that at the bottom they connect these rails, which at the

top are connected by a plate 40 and are lifted, while taking along the rails 56 and 59 , by the rotation of a cam disc 41 corresponding to the disc 18 and co-operating with a lug 42 provided on the plate 40 .

By means of a lug 43 , disposed on the plate 40 and adapted to slide in a slot 44 in the bolt $22a$, and a lug 45 provided on the bolt and adapted to slide in a slot 46 in the plate 40 , the plate 40 and the bolt $22a$ are guided relatively to one another in such a manner that the plate 40 , from the position shown in Figures 7 and 8 in which the lock is closed, can slide downwardly against the pressure from a spring 47 provided between the lugs 43 and 45 . At their upper side, the keys $9a$ are fitted with projecting parts 48 which have oblique parts 49 co-operating with the plate 40 , so that the said keys, when the plate 40 is moved to the bottom of the space formed between the oblique edges 49 , will move all the keys into the "normal position", i. e. the position in which the handles of all the keys are standing in line. The plate 40 is moved further from this position by a rotation of the disc 41 in the direction of the arrow a , effected by means of the handle or the key 19 , the said disc 41 being fitted with an incision, the outer edge 50 of which, during the rotation of the disc in this direction, co-operates with the lug 42 provided on the plate 40 and moves the plate 40 downwardly in the vertical direction of the lock, whereby the said plate, as mentioned above, returns to normal position any keys $9a$ which might have been displaced by an unauthorized person attempting to open the lock. By devices not shown on the drawings and not forming any part of the invention, the bolt $22a$ is connected in such a manner to the latch that when the lock is closed, it will be in its uppermost position, as shown in Figures 7 and 8, but when the lock is open it will be lowered into the position shown in Figure 6 and, during this lowering will have carried along the plate 40 , which consequently rests on the bottom of the notch formed by the oblique notches 49 .

As mentioned at the beginning of the description of this second construction of the lock, the blocking device $8'$ for the sliding keys $9a$ is shaped as a grid consisting of rods disposed between the two rails 39 which are free to slide in the vertical direction of the lock. When the grid is moved up towards the keys, or vice versa, the teeth $11a$ will be forced into the spaces between the grid bars, in such a manner that the latter will take hold of the teeth, thereby preventing the keys $9a$ being displaced.

The rail 59 is connected, in suitable manner, to the bolt $22a$ or to the latch of the lock so that the vertical motion of the bolt or, respectively, the motion of the latch from the closed to the open position of the lock will be prevented as long as the rail 59 is not displaced from the position shown in Figure 7. This displacement is effected by an oblique edge 51 on a rail 52 adapted to slide in the vertical direction of the lock and fitted with a lug 53 , which by the rotation of the key 19 in the direction indicated by the arrow b through an arm 54 , is moved downward and by simultaneously lowering the rail 52 the oblique edge will actuate a lug 55 (see Fig. 14) provided on the rail 59 , whereby the rail 59 is moved sideways (to the right in Figure 7), which motion releases the latch which now, while actuated by a spring or in some other suitable manner, is moved into such a position that the lock is opened.

This arrangement acts in the following manner:

By the rotation of the key 19 in the direction indicated by the arrow *a*, the keys 9a are moved into normal position. Then the keys are pushed into the positions desired, and the lock is opened by a rotation of the handle or key 19 in the direction given by the arrow *b*. By this rotation of the handle or key 19, the periphery of the disc 41 will actuate the lug 42 provided on the plate 40 so as to lift the plate 40 and consequently the rails 39, whereby the grid 8' as well as the rail 56 with the locking members 58 and the rail 59 will be moved upward towards the keys. During the lifting of the grid, the keys 9a will first be blocked, in that the teeth 11a enter into the spaces between the grid bars, and during the continued lifting the teeth 11a situated above the locking members 58 will cause the locking members situated below to slide vertically in their bearings. If the keys 9a have not been properly adjusted, the locking members will be displaced, and consequently the rail 59 cannot slide in the horizontal direction. Owing to the keys 9a blocking the grid 8' it will be impossible to ascertain by feeling what keys are striking the locking members, and what keys are free. If all the keys are properly adjusted, all the locking members will be moved downward and, consequently, the rail 52 when depressed by the arm 54, during the further rotation of the key, will be able to move the rail 59, and the lock will thereby be opened.

It appears from the above that in both constructions of the block a blocking of the keys will at once be effected when it is attempted to open the lock after an adjustment of the keys, and only after the keys have been blocked in the positions given to them will the locking members and keys come into contact with one another, so that it will be impossible to feel what key teeth are in contact with the locking members, and what are free.

The construction of the lock may be varied in different ways, without deviation from the principle underlying the invention, which principle is that the units causing the displacement of the locking members should be blocked, so that they are held in the position given them, during this displacement, and maybe before the same takes place.

Having now described my invention what I claim as new and desire to secure by Letters Patent is:

1. A combination lock comprising a lock bolt, means comprising a plurality of movable locking members for retaining the bolt normally in locking position, mechanism for moving said locking members to bolt releasing position comprising a plurality of individually manually adjustable members, and blocking means cooperating with said adjustable members for retaining the latter in previously adjusted position during the operation of said mechanism.

2. A combination lock comprising a lock bolt, means comprising a plurality of movable locking members for retaining the bolt normally in locking position, mechanism for moving said

locking members to bolt releasing position comprising a plurality of individually manually adjustable members, and blocking means cooperating with said adjustable members, and arranged for operation by said mechanism for retaining the latter in previously adjusted position during the operation of said mechanism. 5

3. A combination lock comprising a lock bolt, means comprising a plurality of movable locking members for retaining the bolt normally in locking position, mechanism for moving said locking members to bolt releasing position comprising a plurality of individually manually adjustable members, and blocking means cooperating with said adjustable members and arranged for operation by said mechanism during the initial portion of the operation thereof for retaining the latter in previously adjusted position during the operation of said mechanism. 10

4. A combination lock comprising a lock bolt, means comprising a plurality of movable locking members comprising spring pressed pins for retaining the bolt normally in locking position, mechanism for moving said locking members to bolt releasing position comprising a plurality of individually manually adjustable members, and blocking means cooperating with said adjustable members for retaining the latter in previously adjusted position during the operation of said mechanism. 20

5. A combination lock comprising a lock bolt, means comprising a plurality of movable locking members comprising spring pressed balls for retaining the bolt normally in locking position, mechanism for moving said locking members to bolt releasing position comprising a plurality of individually manually adjustable members, and blocking means cooperating with said adjustable members for retaining the latter in previously adjusted position during the operation of said mechanism. 30

6. A combination lock having a casing, a manually movable cam member therein, a reciprocal lock member actuatable by said cam in one direction to unlocking position, a transversely disposed rail movable by said cam in the opposite direction, a plurality of locking members carried by said rail, a laterally shiftable rail carried by said first rail and normally retained against relative shifting movement by said locking members, means carried by said second mentioned rail for obstructing movement of said lock member to unlocking position, a plurality of manually adjustable members adapted to be adjusted in predetermined positions and arranged when in such positions to cooperate with said locking members during movement of said first rail to release said second rail to enable the same to be shifted laterally from obstructing position with respect to said lock member, and a blocking member moved by said first rail upon initial movement of the latter by said cam into engagement with said adjustable members to prevent re-adjustment of the latter during operation of the lock. 45

LOUIS PAUL GEORG KETNER. 50
